UNITED STATES PATENT OFFICE.

ANDREW P. HANSEN, OF OMAHA, NEBRASKA.

HORSE-CHECKING DEVICE.

SPECIFICATION forming part of Letters Patent No. 695,390, dated March 11, 1902.

Application filed May 18, 1901; Serial No. 60,890. (No model.)

To all whom it may concern:

Be it known that I, ANDREW P. HANSEN, a citizen of the United States, residing at and whose post-office address is No. 3450 South Fifteenth street, Omaha, in the county of Douglas and State of Nebraska, have invented new and useful Improvements in Horse-Checking Devices, of which the following is a specification.

10 This invention relates to horse-checking devices, the object in view being to provide, in connection with a vehicle, means whereby the draft-animals in case they attempt to run away may be checked and brought to a stand-
15 still.

To this end the invention consists in mounting the whiffletree in such manner that it may be released and allowed to slide a limited distance lengthwise of the draft pole or tongue, 20 such arrangement, in connection with a fixed check-strap which connects with the bridles of the animals, serving to draw the heads of the animals together, and thereby bending the necks of the animals and making their 25 positions so awkward that it will be impossible for them to run for any great distance.

Other objects and advantages of the invention will appear more fully in the course of the ensuing description.

30 The invention consists in a horse-checking device embodying certain novel features and details of construction and arrangement of parts, as hereinafter fully described, illustrated, and claimed.

35 In the accompanying drawings, Figure 1 is a plan view of a portion of a draft pole or tongue, showing the sliding whiffletree and check-strap. Fig. 2 is a longitudinal section through the same, showing the check-strap in 40 elevation. Fig. 3 is a side elevation of the parts, showing the whiffletree in section. Fig. 4 is a cross-section through the tongue and check-strap, showing the whiffletree and keepers in elevation.

45 Similar numerals of reference designate corresponding parts in all figures of the drawings.

Referring to the drawings, 10 designates the draft pole or tongue of a vehicle, and 11 50 the whiffletree or doubletree, which is under ordinary conditions pivotally connected to the tongue by means of a pin 12, provided at

its upper end with a head 13, the whiffletree being arranged above the tongue in the ordinary manner.

55 The pivot pin or bolt 12 is held in place by means of a pin-retaining keeper 14, preferably in the form of a spring, the free end of which extends over and lies upon the head of the pivot-pin and the opposite end of 60 which is secured to the whiffletree, as at 15, by means of a headed fastener, which will allow the spring to be swung to one side or the other out of engagement with the head of the pin for permitting said pin to jump out of 65 place or be withdrawn by the driver, with the result that the whiffletree will be allowed to slide forward on the draft pole or tongue.

In order to prevent the whiffletree from escaping from the tongue and to guide said 70 whiffletree in its sliding movement, oppositely-located keepers 16 are connected to the lower side of the whiffletree, as best shown in Fig. 4, and provided with inbent terminal portions or extremities 17, which enter longitudinal grooves 18 in the opposite sides of the tongue 10. In the forward sliding movement of the whiffletree the keepers 16 come in contact with a stop-ring 19, surrounding the tongue and having a fixed relation thereto. In this way a limited sliding movement 75 is allowed for the whiffletree after it is freed from its pivotal connection with the tongue. 80

A check-strap 20 is secured at its rear end to the running-gear or to the brake mechanism where the vehicle is equipped with such, while the forward end of said strap is bifurcated or provided with branches 21, which are secured to the inside portions of the bridles of the horses or draft-animals. The 90 check-strap is fixed and incapable of sliding, so that when the whiffletree is freed and drawn forward by the animals the branches 21 of the check-strap operate to draw the animals' heads together, thus bending their necks 95 and making their positions so awkward as to render it impracticable to run away. The pin-retaining keeper 14 is arranged with its free end extending rearward, so as to be in convenient position to be kicked to one side or the other by the driver's foot or be swung in either direction by hand. When the keeper has been disengaged from the head of the pin, 100 the pin will, by reason of the jolting of the

vehicle, jump out of place, and should this not occur quickly enough the driver may lift the pin out of place thereby freeing the whiffletree, with the result hereinabove described.

I do not desire to be limited to the exact arrangement hereinabove set forth, but reserve the right to change, modify, or vary the construction within the scope of the appended 10 claims.

Having thus fully described my invention, what I claim as new, and desire to secure by Letters Patent, is—

1. In a horse-checking device, the combination with a vehicle pole or tongue, of a whiffletree adapted to slide bodily on and lengthwise of the tongue, means for pivotally connecting the whiffletree to the tongue and releasing the whiffletree, and a check-strap 20 operating to draw the animals' heads to one side during the sliding movement of the whiffletree.

2. In a horse-checking device, the combination with a vehicle pole or tongue, of a 25 whiffletree having a sliding engagement

therewith, a pivot-pin connecting the whiffletree and tongue, a pin-retaining keeper adapted to be thrown out of engagement with the pin for releasing the latter, and a check-strap adapted to draw the animals' heads together 30 when the whiffletree is released.

3. In a horse-checking device, the combination with a vehicle pole or tongue provided with longitudinal grooves in opposite sides thereof, of a whiffletree adapted to slide 35 lengthwise of the tongue and having keepers working in the grooves in the tongue, a pivot-pin connecting the whiffletree and tongue, a shiftable pin-retaining keeper carried by the whiffletree, and a check-strap having one end 40 connected to the vehicle and the opposite end bifurcated to form branches for attachment to the bridles of the animals.

In testimony whereof I affix my signature in presence of two witnesses.

ANDREW P. HANSEN.
